UNITED STATES PATENT OFFICE.

DE WITT J. CURTISS, OF ONEIDA, NEW YORK.

SAFETY DEVICE.

1,176,656.

Specification of Letters Patent. Patented Mar. 21, 1916.

Application filed October 23, 1914. Serial No. 868,317.

To all whom it may concern:

Be it known that I, DE WITT J. CURTISS, a citizen of the United States, residing at Oneida, in the county of Madison and State 5 of New York, have invented new and useful Improvements in Safety Devices, of which the following is a specification.

This invention relates to improvements in safety devices for use on stamping and 10 die presses to prevent the possibility of the hands of the operator from being injured during the operation of the press, the object of the invention being to provide an improved safety device of this character, 15 which is cheap and simple, which may be readily attached to and used in connection with any ordinary stamping or die press, and which also may be readily adjusted as required.

20 The invention consists in the construction, combination and arrangement of devices hereinafter described and claimed.

In the accompanying drawings:—Figure 1 is a front elevation of a portion of a die 25 or drop press provided with improved safety devices constructed in accordance with my invention. Fig. 2 is a side elevation of the same. Fig. 3 is a detail sectional view.

30 For the purposes of this specification the bed of an ordinary press is indicated at 1, dies are indicated at 2 and the usual upwardly extending standard or upright is indicated at 3. The drop, hammer or 35 punch is indicated at 4 and is vertically movable in a guideway 5 with which the standard or upright is provided.

In accordance with my invention I provide a pair of supporting arms 6 which are 40 attached to opposite sides of the standard and extend forwardly therefrom and are adjustable so that their outer ends may be raised or lowered as required. A rock shaft 45 7 is mounted in bearings near the outer ends of said arms and is provided with a series of fender arms 8 which have upwardly extending arms 9 that pass through transverse openings in the rock shaft and are secured thereto in adjusted position by 50 set screws or other suitable devices 9^a thus adapting the fender arms to be adjusted as

may be desired. The rock shaft has a rock arm 10 near one end to which is attached a spring 11 which serves to turn the rock shaft so as to raise the fenders and turn them inwardly toward and above the dies. The rock shaft also has a tappet arm 12 which extends inwardly therefrom. The drop 4 is provided on one side with a laterally extending tappet stud 13 which engages with the tappet arm 12 as the drop descends, which in turn turns the rock shaft so as to move the fenders outwardly. This outward movement of the fenders will force the hand of the operator away from the dies 60 and thus effectually prevent the operator's hand from being caught in the press. On the ensuing up stroke of the drop the spring 11 turns the rock shaft and fenders in the opposite direction thus permitting the work 65 to be fed to the press.

While I have herein shown and described a preferred form of my invention I would have it understood that changes may be made in the form, proportion and construction of the several parts without departing from the spirit of the invention and within the scope of the appended 75 claims.

Having thus described my invention, I 80 claim:—

1. In combination with the standard and drop of a die or other like press, supporting elements adjustably attached to the standard, a rock shaft mounted in said supporting elements, fenders carried by and adjustable on the rock shaft, a spring to turn the rock shaft and fenders in one direction, a tappet arm projecting from the rock shaft, and a tappet carried by the drop to 90 engage the tappet arm of the rock shaft when the drop descends and thereby cause the fenders to be moved outwardly.

2. In combination with the standard and drop of a die or other like press, supporting elements adjustably attached to the standard, a rock shaft mounted in said supporting elements, a plurality of longitudinally aligned fenders, carried by and adjustable on the rock shaft, a spring connected 95 to the rock shaft adjacent one end thereof for turning the rock shaft and fenders in 100

one direction, a tappet arm projecting inwardly from the rock shaft at a point adjacent its opposite end, and a tappet carried by the drop to engage the tappet arm of
5 the rock shaft when the drop descends and thereby cause the fenders to be moved outwardly.

In testimony whereof I affix my signature in presence of two witnesses.

DE WITT J. CURTISS.
